US0D1102156S

(12) **United States Design Patent** (10) **Patent No.:** **US D1,102,156 S**
(45) **Date of Patent:** **** Nov. 18, 2025**

(54) **PACKING STRAP**

(71) Applicant: **Zhejiang Youngsun Machinery Co., Ltd.**, Zhejiang (CN)

(72) Inventor: **Bangyi Luo**, Zhejiang (CN)

(73) Assignee: **Zhejiang Youngsun Machinery Co., Ltd.**, Hangzhou (CN)

(**) Term: **15 Years**

(21) Appl. No.: **29/929,677**

(22) Filed: **Feb. 23, 2024**

(30) **Foreign Application Priority Data**

Sep. 1, 2023 (CN) 202330567694.7

(51) **LOC (15) Cl.** **03-99**

(52) **U.S. Cl.**

USPC **D3/328**

(58) **Field of Classification Search**

USPC D9/434-436, 440, 443, 447, 499, 453,
D9/452, 456; D3/328

CPC B65D 5/5016; B65D 1/36

(57) **CLAIM**

The ornamental design for a packing strap as shown and described.

DESCRIPTION

FIG. 1 is a front elevational view of a packing strap showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front-right-bottom perspective view thereof;

FIG. 8 is a front-right-top perspective view thereof;

FIG. 9 is a rear-left-top perspective view thereof;

FIG. 10 is an enlarged view of FIG. 5;

FIG. 11 is an enlarged view of FIG. 6;

FIG. 12 is an enlarged view taken from section 12 of FIG. 3; and,

FIG. 13 is an enlarged view taken from section 13 of FIG. 4.

In the drawings, the broken lines represent enlarged designations that form no part of the claim.

1 Claim, 13 Drawing Sheets
